US00D821437S

(12) **United States Design Patent** (10) **Patent No.:** **US D821,437 S**
Chaudhri et al. (45) **Date of Patent:** **** Jun. 26, 2018**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Imran Chaudhri**, San Francisco, CA (US); **Jorge Fino**, San Jose, CA (US); **Stephen O. Lemay**, San Francisco, CA (US)

(73) Assignee: **Apple Inc.**, Cupertino, CA (US)

(**) Term: **15 Years**

(21) Appl. No.: **29/624,142**

(22) Filed: **Oct. 30, 2017**

Related U.S. Application Data

(63) Continuation of application No. 29/575,594, filed on Aug. 26, 2016, now Pat. No. Des. 801,367, which is a continuation of application No. 29/483,803, filed on Mar. 3, 2014, now Pat. No. Des. 765,092.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
